CLAIM

The ornamental design for a shopping device, as shown and described.

DESCRIPTION

FIG. 1 is a right side, front, and top perspective view of a shopping device showing the new design;
FIG. 2 is a left side, front, and top perspective view thereof;
FIG. 3 is a left side, rear, and top perspective view thereof;
FIG. 4 is a right side, rear, and top perspective view thereof;
FIG. 5 is a right side, front, and bottom perspective view thereof;
FIG. 6 is a left, front and bottom perspective view thereof;
FIG. 7 is a left side, rear, and bottom perspective view thereof;
FIG. 8 is a right side, rear, and bottom perspective view thereof;
FIG. 9 is a top view thereof;
FIG. 10 is a front view thereof;
FIG. 11 is an enlarged side view thereof; other side being a mirror image thereof;
FIG. 12 is a rear view thereof; and,
FIG. 13 is a bottom view thereof.
The broken lines in the drawings depict portions of the shopping device that form no part of the claimed design.

1 Claim, 13 Drawing Sheets
